William Bennett
Grates Patent

Nov 19, 1833

The Grates referred to in these Grates Patent and making part of
the same containing a description in the words of the said William Bennett
of his Improvement in Furnaces for burning Anthracite
and for heating & evaporating Liquids.

To all whom it may concern. Be it known that William Bennett of
Malden in the County of Middlesex and State of Massachusetts have invented
a certain improvement in furnaces for the purpose of burning the different
varieties of Anthracite coal and applying the heat from the same to the heat-
ing of objects used for the purpose of Dying, Distilling, Boiling, Soap-making,
Generating Steam, and in general whatever is required to heat or to evap-
orate fluids of any kind by a thick insertion or improvements I refer to a con-
siderable extent the use of fuel and the time required for attendance on
the fire, effect a more rapid heating of the fluids by a more immediate applica-
tion of the fire to the bottom of the containing vessel and with ease of applying
the fire with greater facility than by any of the methods hitherto
known, prevent the great heat from the effects of the intense heat of the fire
and obtain other advantages. The grate with its appendages which
is used for sustaining the fuel is made to run upon a rail way by means
of iron trucks or rollers, from which circumstance I denominate the furnace
the "railway furnace" and I do hereby declare that the following is a full
and exact description of the construction thereof, reference being had to the
drawings which accompany and make a part of this specification. Fig. 1 is
a sectional view of the furnace cast metallicly from iron to be hot. Fig. 2 is
a vertical transverse section thereof. Fig. 3 is a horizontal section or plan with
a boiler and a fire-tube which surrounds it, removed leaving the furnace
and its immediate appendages in view. Fig. 4 shows the under side of the
grate, its spars and trucks, &c. Trucks upon which it runs. Fig. 5 is a side
view of the same. Fig. 6, the upper surface of one of the bars. Fig. 7 is a trans-
verse section of the same. In referring to the respective figures I shall merely

1784 X

of them represent the corresponding parts of the same frame. As Fig. 1 is the back, or unrounded by the back, frame and other appendages the form of which however, will be sufficient to give the notion of the business to be performed.

B is the Ark Ark within which is contained the furnace and the earthenware which it is to receive. C is the base of the grate made of cast iron. D the cast iron in which they run. E the trucks or rollers provided to keep them in their place, both these latter parts also being usually made of cast iron. E. Fig. 2 shows the earthenware frame upon which the projecting pieces are cast to receive the trucks and at the side. F. there is a flange or fillet along the whole length projecting downwards, this part over hangs an opening of wide proportions the manner of the cast immediately under the furnace and firmly attached to the machinery by large or projecting pieces of wrought iron bolted into it. This arrangement is shown at F. Fig. 2. it serves to secure and direct the current of air through the openings between the base by presenting obstacles to its lateral motion. These flanges or fillets are made to project more to touch each other and thereby offer any obstruction to the transmission of the furnace. To secure a sufficient degree of strength on the cast iron frame which contains the grate base it is made in one entire piece with rebates for the reception of the Castle Bars. This is also made of greater thickness and will bear the load than elsewhere. What I denominate the "casing" of the furnace and which is intended to prevent the entrance of air above the fuel when the furnace is in its place. Ordinarily made of a thick plate of sheet iron. The lower edge of this plate fits on to the front edge of the cast iron frame of the furnace to which it is firmly attached and its upper edge shuns closely against a fillet or ledge on the lower side of a cast iron "casing" plate upon which plate the machinery is carried over the furnace in constructing the back and fire around the latter. The manner in which the cast plate shuns may be seen by inspecting that part of the instrument as in the drawing, fig. 1. A large or square frame of thick sheet iron. B. fig. 2 is made of iron and attached to the furnace frame. This serves to receive the lining of brick stone or other bad conductors of heat. It serves in otherwise to turn the proper shape for the place it is to occupy. To this short compass is added to the cast iron frame of the furnace. Between the iron plate by means of

of both bars at all, helping it at such distance from the fuel as may be (as in a furnace or a furnace) the bars being regulated by the number of the bars and the space. The bars have high, broad, flat grooves or channels along them, making this groove about three fourths of an inch deep through the entire length. The outer top, shows the general form of the bars. Projections at the ends and at the middle of each bar make in the ordinary form some to keep them when in their places at regular distance from each other. The upper rounded spaces in the bars protect them from injury by the intense heat of the fuel, which it does not only by surrounding the parts of contact with it but also by reducing the heat which has a wheel ^{heat of} a bad conductor. I have thus described the construction of my furnace such as those of an anthracite and the drawings thereof which are however attached. They made to a scale of one inch and a half to the foot taking said furnace for my guide. It will be manifest however that it may not only be various in size but that the parts may in many instances be differently arranged whilst the principle of construction remains unchanged. I do not intend therefore by this description to confine myself in either of these particulars but to make such construction as experience or convenience may dictate. What I claim as new in the furnace herein described is that arrangement thereof by which I am enabled to bring the burning fuel, anthracite, much nearer to the bottom of the vessel to be heated than can be effected by any of the ordinary modes of construction, namely by making the furnace in the general form described and running the bars upon a rail may also not claim as my invention the increasing of a furnace upon a railway, this having been before done or proposed to be done in few places of a certain description. But I claim it only in combination with the kind of furnace which I have described. I also claim the manner of forming and directing the bars between the grate bars by means of the large flat iron filled at each side of and beneath the space of the furnace. I also claim in the particular construction of the bars bars grooved on their upper side on the manner and for the purpose above set forth.

Witnessed to on this

22d day of November, 1851.
